US00D850414S

(12) **United States Design Patent** (10) **Patent No.:** **US D850,414 S**
Desagre et al. (45) **Date of Patent:** **** Jun. 4, 2019**

(54) **REMOTE CONTROL**

- (71) Applicant: **SOMFY SAS**, Cluses (FR)
- (72) Inventors: **Thomas Desagre**, Lyons (FR); **Frederic Strubi**, Lyons (FR); **Philippe Bajard**, Lyons (FR)
- (73) Assignee: **SOMFY SAS**, Cluses (FR)
- (**) Term: **15 Years**
- (21) Appl. No.: **29/613,444**
- (22) Filed: **Aug. 10, 2017**

Related U.S. Application Data

- (62) Division of application No. 29/539,963, filed on Sep. 18, 2015, now Pat. No. Des. 798,272.

(30) **Foreign Application Priority Data**

- Mar. 20, 2015 (WO) DM/085946

(57) **CLAIM**

The ornamental design for a remote control, as shown and described.

DESCRIPTION

FIG. 1 is a perspective exploded view of a remote control according to our invention;

FIG. 2 is a front view thereof;

FIG. 3 is a left side view thereof;

FIG. 4 is a right side view thereof;

FIG. 5 is a back view thereof;

FIG. 6 is a bottom view thereof; and,

FIG. 7 is a top view thereof.

The broken lines in the figures represent portions of the remote control which form no part of the claimed design.

1 Claim, 4 Drawing Sheets
